UNITED STATES PATENT OFFICE

OTTO ANDREAS ANDERSON, OF CHICAGO, ILLINOIS

DESIGN FOR A DAVENPORT OR SIMILAR ARTICLE

Application filed January 25, 1932. Serial No. 42,621. Term of patent $3\frac{1}{2}$ years.

To all whom it may concern:

Be it known that I, OTTO ANDREAS ANDERSON, a citizen of the United States, residing at Chicago, in the county of Cook and State of Illinois, have invented a new, original, and ornamental Design for a Davenport or Similar Article, of which the following is a specification, reference being had to the accompanying drawing, forming a part thereof.

The figure is a perspective view of the davenport embodying my invention.

I claim:

The ornamental design for a davenport or similar article, as shown.

In witness whereof, I hereunto subscribe my name this 14th day of November, 1931.

OTTO ANDREAS ANDERSON.
